(57) **CLAIM**

The ornamental design for a rim protector, as shown and described.

DESCRIPTION

FIG. 1 is a front, bottom perspective in the environment of an unclaimed wheel of a rim protector according to one embodiment of the invention.

FIG. 2 is a front, top, right side perspective of a rim protector of FIG. 1.

FIG. 3 is a rear, bottom, left side perspective view of the rim protector of FIG. 1.

FIG. 4 is a front elevation view of the rim protector of FIG. 1.

FIG. 5 is a rear elevation view of the rim protector of FIG. 1.

FIG. 6 is a left side elevation view of the rim protector of FIG. 1.

FIG. 7 is a right side elevation view of the rim protector of FIG. 1.

FIG. 8 is a top plan view of the rim protector of FIG. 1; and, FIG. 9 is a bottom plan view of the rim protector of FIG. 1. The broken lines shown in the drawings are for environmental purposes only and form no part of the claimed design.

1 Claim, 7 Drawing Sheets

FIG. 2

FIG. 4

FIG. 7

FIG. 6
